Primary Examiner — T. Chase Nelson(74) *Attorney, Agent, or Firm* — Kilpatrick Townsend & Stockton LLP(57) **CLAIM**

The ornamental design for a footwear grip, as shown and described.

DESCRIPTION

FIG. 1 is an isometric view of a footwear grip.

FIG. 2 is a bottom view of the footwear grip of FIG. 1.

FIG. 3 is a side view of the footwear grip of FIG. 1.

FIG. 4 is another side view of the footwear grip of FIG. 1; and, FIG. 5 is another bottom view of the footwear grip of FIG. 1, shown in the environment of the bottom of footwear.

The broken lines form no part of the claimed design.

1 Claim, 2 Drawing Sheets(56)
